Primary Examiner — Eric L Goodman*Assistant Examiner* — Michael Hoffman(74) *Attorney, Agent, or Firm* — Husch Blackwell LLP(57) **CLAIM**

The ornamental design for a respiratory mask, as shown and described.

DESCRIPTION

FIG. 1 is a perspective view of a respiratory mask showing the new design;

FIG. 2 is a front elevation view thereof;

FIG. 3 is a top plan view thereof;

FIG. 4 is a rear elevation view thereof;

FIG. 5 is a bottom plan view thereof; and,

FIG. 6 is a right side elevation view thereof (the left side elevation view is a mirror image of FIG. 6).

The dash-dash type broken lines shown in the drawing views are included for the purpose of showing environmental subject matter that forms no part of the claimed design.

1 Claim, 4 Drawing Sheets(56)
